TYPEWRITER BOX

Edward T. Johnson, Greenfield, Mass., assignor
to The New England Box Company, Greenfield,
Mass., a corporation of Massachusetts

Application September 10, 1935, Serial No. 39,891

6 Claims. (Cl. 217—52)

This invention relates to a shipping package designed to resiliently suspend a relatively heavy, delicate article in the interior thereof and to have an exterior which is relatively strong and rigid so that it will serve to protect the goods.

The package of my invention is particularly suitable for use in shipping heavy machines such as typewriters, calculating machines, precision instruments and the like, and is designed to resiliently support these machines so that the package may be subjected to a considerable amount of rough treatment without any damage to the contents. Ordinarily in shipping such things as typewriters, for example, there is provided a box 10 of wooden or other construction which is very solid and which is made just the right size to fit the machine. The typewriter is then placed in the box and securely wedged in place to prevent relative movement between the box and the typewriter. This type of package is quite suitable if handled very carefully, but there is always the danger that the box may be dropped or struck a blow causing damage to the typewriter since any sudden force applied to the outside of the box is 15 directly transmitted to the machine. Occasionally a special spring mounting is provided between the machine and box but this is complicated and expensive and unsatisfactory for various other reasons.

It is an object of my invention to provide a novel, simple construction whereby the typewriter, or other machine, is spaced from the walls of the container, is locked in the box by simply closing the lid thereof but is resiliently suspended 20 and is free to move a limited amount, insufficient to produce solid engagement with the box walls when the container is subjected to rough handling.

One feature of my invention is the provision of 25 a structure of the character explained which is economical to produce and which, if desired may be made completely of wood.

A further feature is the provision of a box or container of the type specified which is of simple 30 construction and adapted to contain machines of varying sizes and one which may be very readily re-used.

Further features and advantages will be made 35 apparent from the following description of one embodiment of my invention illustrated in the drawings, in which:

Figure 1 is a vertical, transverse cross-section taken near one end of a package formed in accordance with my invention.

Figure 2 is a vertical, longitudinal cross section

through the package showing certain locking means for the resilient machine support, said section being taken on the line 2—2 of Figure 1.

Figure 3 is a vertical cross section through the box on the line 3—3 of Figure 2 showing the resilient support in cross section.

Figure 4 is a plan view of my improved package with the lid removed and having a portion of the resilient support broken away to disclose certain details, and

Figure 5 is a detail in vertical section on the line 5—5 of Figure 4, illustrating one method of attaching a machine to the resilient support.

Numeral 10 indicates generally a box which may be made in a conventional way of wood as 15 illustrated, or of other suitable material. It is preferably of a fairly rigid and solid construction capable of resisting breakage or damage in the course of rough handling when loaded. This box comprises a bottom member 11, lid 12 and side 20 members 13, 14, together with suitable end pieces 15, 16. The side members and end pieces may be joined at the corners in any suitable way as by a dovetail or lock corner construction or the like. Fixed to each of the sides 13, 14 by any 25 suitable means such as nails, screws, or bolts, are pairs of vertically extending cleats 17, 17 and 18, 18 with the top ends 19 thereof spaced from the top edge of the box a convenient distance, for a purpose to be described.

The resilient support for the machine contained in the package preferably comprises a section of ply wood 21, which is adapted to rest directly on the ends of the fixed cleats 17, 17 and 18, 18. I have found a $\frac{1}{16}$ " or $\frac{3}{20}$ " ply wood 35 sheet quite satisfactory for supporting a typewriter. Fixed to opposite edges on the underside of and centrally disposed on this resilient support are two cleats 22, 22 which are of the right length to snugly fit between the pairs of vertically 40 extending cleats 17, 17 and 18, 18 to prevent side or edgewise movement of the resilient support longitudinally with respect to the box. Carried on the top of the support and directly above the cleats 22, 22 are a pair of locking cleats 23, 23, 45 which are of the correct thickness to take up the space between the resilient support and the lid of the box.

It will be seen from the foregoing that two of the end edges of the resilient support are firmly 50 locked in place against any form of movement with respect to the box when the package is in its assembled position and the lid is firmly fastened down. Upward movement is prevented by the cleats 23 acting against the cover; downward 55

movement is prevented by cleats 17 and 18; transverse movement (i. e., across Figure 1) is prevented by engagement of the cleats 22 and 23 as well as the ends of the ply wood with the walls 5 13 and 14, while longitudinal movement (i. e., across Figure 2) is prevented by cleats 22 acting on cleats 17 and 18. Since the section of ply wood, or similar material 21, is resilient and flexible those portions of it intermediate the end 10 edges will be free to move up and down a limited extent but it will always tend to substantially straighten out. Thus this member serves as a resilient support for anything attached to it.

The machine or other merchandise to be packed 15 is preferably rigidly mounted on the support 21 so that it hangs downwardly in the box. Any suitable means may be employed to fix the machine to the flexible support.

In the drawings I have illustrated one type of 20 means which I prefer to employ for shipping typewriters. Typewriters ordinarily have four legs which may very readily be made hollow and threaded. These legs or standards of the machine may be spaced from the flexible support by 25 a pair of cleats 24, 24 and suitable washer members 25, as best shown in Fig. 5. Cleats 24 are provided with holes 26 to receive bolts 27 and are also preferably undercut as at 28 in any suitable manner, to provide room for cup shaped washers 30, which are fitted in holes 30 in the ply wood member 21. Suitable lock washers 31 may be employed if desired. It will be understood that the assembly is maintained by the bolts 27. By 30 the use of the various washer members and cleats 35 very little, if any, strength of the resilient support is sacrificed. In fact the cleats tend to stiffen the support somewhat although not to an objectionable extent, particularly since they are not secured to the ply wood except by means of the bolts 27. It will be apparent that in supporting 40 heavy machines, such as typewriters and calculating machines, it is necessary to make the structure rather sturdy and too great a flexibility is not desirable.

45 In packing a box of the foregoing construction for the shipment of a typewriter, the resilient support 21 is first firmly attached to the legs or other portion of the typewriter as by an arrangement of the type just described. The ply wood sheet 21 is then grasped along its free edges 50 with the typewriter hanging downwardly and the latter is then lowered into the box in such a way that the cleats 22 fit into locking position between the cleats 17 and 18. The ply wood layer 21 is preferably of the right length to fit across 55 the box but it is not as wide as the length of the box thus leaving spaces at the two opposite edges adjacent the box ends 15 and 16 so that the machine may be readily lowered and raised without 60 injuring the hands. Furthermore, this arrangement makes it possible to employ the same sized ply wood boards for typewriters having carriages of different lengths. The mere fact that a larger box is required for a larger carriage does not 65 necessitate a change in the size of the ply wood support. The cleats 23 are flush with the top of the box so that when the lid is closed and firmly secured the typewriter is locked in its correct position, spaced from all of the six walls of the box 70 and free to move, in opposition to the yielding restraining force of the ply wood, whenever the box is jarred.

75 As previously stated, the box may be very advantageously made with a lock corner or a dovetail construction although any other suitable con-

struction may be employed. It should be formed of wood of suitable thickness to withstand the roughest handling to which the box is likely to be subjected. The bottom, which is the most vulnerable part of the box, should be made somewhat thicker than the sides and top. I also prefer to apply one or more metal bales or bands of some type around the exterior of the box to lend further strength. Such a shipping package combines interior flexibility with exterior strength 10 and rigidity. Furthermore, the construction may be readily standardized so that a relatively small number of different sized parts will accommodate a large variety of machines. The box may very readily be reused by simply lifting out one machine and replacing it by another which need not be of identically the same size so long as the 15 ply wood support and its cleats are appropriate.

Many modifications may be employed within 20 the scope of my invention. For example, the cleats 23, 23 could be nailed to the lid of the box rather than to the resilient support 21. If desired, one of the cleats 22 may be made longer than the other and the cleats 17, 17 and 18, 18 spaced apart different distances so that the machine to be shipped will fit in the box in only one position. Any other suitable locking means might also be employed although I prefer the construction illustrated because of its simplicity 25 of manufacture and use.

The resilient support may, if desired, be of the 30 same dimensions as the interior of the box and have cut out portions or handles so that it may be easily lifted. In this case the cleats 22 may be omitted.

If the machine to be suspended is not equipped 35 with legs or standards having screw threaded openings to receive the bolts 27 the latter may simply be passed through eyelets on a looped wire, or bail, or the like which may be engaged 40 under a suitable portion of the machine frame to support the same.

If desired, the cleats 22 might be omitted and 45 their function supplied by other means. For example, the vertical cleats 17, 18 might be partly 50 cut away at their tops to provide shoulders for receiving and supporting the ply wood member and to provide upstanding fingers cooperating 55 with the edges of the ply wood to prevent lateral movement thereof.

To assist in distributing the pressure of the 60 supporting member on the walls of the box during endwise movement of the support the cleats 22 may be partly cut away at their ends to provide a portion on each snugly fitting between the vertical cleats 17, 17 or 18, 18 and portions at the 65 ends overlying these vertical cleats. In this way the thrust will be transmitted, at least in part, to the cleats 17 and 18 which will in turn distribute the pressure over a greater portion of the 70 walls 13 and 14.

Numerous other variations in the details of 75 construction will suggest themselves to persons skilled in the art.

The terms and expressions employed herein are 80 used for purposes of description and not of limitation. It is recognized that many modifications of the construction disclosed may be made within the scope of the present invention.

What I claim is:

70 1. A shipping package of the class described, comprising a relatively strong and rigid container, a flexible support in sheet form spaced from the top and bottom of said container, said support having its ends resting on supports fixed to 75

the inside walls of the container, and a cover for said container constructed and arranged to hold said support removably in place.

2. A shipping package of the class described, comprising a relatively strong and rigid container, means fixed to the inner side of the walls of said container, a flexible support in sheet form supported at its edges by said means, and means between said support and the container cover 10 to prevent upward movement of said support when the cover of the container is in place, said last named means being unattached to said walls.

3. A shipping package of the class described, comprising a relatively strong and rigid container, means fixed to the inner side of the walls of said container, a flexible support in sheet form supported at its edges by said means, means to prevent upward movement of said support when the cover of the container is in place, and means 20 coacting with said first named means to prevent edgewise movement of said support relative to the container.

4. A shipping package comprising a container for relatively heavy, delicate merchandise, a resilient support comprising a sheet of ply wood, 25 cleats fixed to opposite inner walls of the contain-

er and arranged to receive said support, cleats fixed to said support adjacent opposite edges thereof and adapted to prevent lateral movement of said support when it rests on the first mentioned cleats, and means to lock the edges of 5 said support in place only when the lid of said container is applied.

5. A shipping package comprising a container for relatively heavy, delicate merchandise, a resilient support comprising a sheet of ply wood, 10 cleats fixed to opposite inner walls of the container and arranged to receive said support, cleats fixed to said support adjacent opposite edges thereof and adapted to prevent lateral movement of said support when it rests on the first mentioned cleats, and means carried by said support 15 cooperating with the lid for holding the support in position when the lid of the container is applied.

6. A shipping package as defined in claim 5 in 20 which the flexible support is supported only at its ends with side edges thereof spaced from the walls of the container, and means for preventing lateral movement of said support in said container when the cover is closed. 25

EDWARD T. JOHNSON.
